SHADE ROLLER AND FASTENER

Filed June 9, 1930

UNITED STATES PATENT OFFICE

STEWART HARTSHORN, OF SHORT HILLS, NEW JERSEY, ASSIGNOR TO STEWART HARTSHORN COMPANY, OF EAST NEWARK, NEW JERSEY, A CORPORATION OF NEW JERSEY

SHADE ROLLER AND FASTENER

Application filed June 9, 1930. Serial No. 459,903.

The present invention relates to shade rollers in general, but more particularly to rollers of the type having an outer metallic sheath.

An object of the invention is to provide means whereby a curtain shade may be quickly and easily attached to its roller and whereby the attached curtain shade is firmly held on its roller against force applied to the shade during its use.

Another object of the invention is to provide improved means, whereby a shade roller may be so constructed as to enable its length to be readily adjusted to suit the requirements of any particular conditions, and yet may be manufactured at little additional cost.

A further object of the invention is to provide a shade roller construction enabling the length of the roller to be readily adjusted and also enable quick and easy attachment of the shade to the roller.

These and further objects will more fully appear in the following description taken in connection with the accompanying drawings, in which Fig. 1 is a view in elevation of an adjustable shade roller; Fig. 2 is an enlarged fragmental view in elevation of the shade roller rotated approximately 180° away from its position shown in Fig. 1, and having thereon a shade fabric and a plurality of fasteners securing the fabric to the roller; Fig. 3 is a perspective view of an improved shade fastener; Fig. 4 is an enlarged fragmental longitudinal sectional view of the shade roller taken on the plane indicated by the line 4—4 of Fig. 1, showing improved means for adjusting the length of the rollers; Fig. 5 is a cross-sectional view of the roller as taken on the plane indicated by the line 5—5 of Fig. 4; Fig. 6 is a fragmental longitudinal sectional view of a shade roller showing a possible construction thereof; Fig. 7 is a view of the top edge portion of the shade fabric having openings formed therethrough; Fig. 8 is an enlarged cross-sectional view on the plane indicated by the line 8—8 of Fig. 2; and Fig. 9 is a similar view on the plane indicated by the line 9—9 of Fig. 2.

In carrying out the invention, the fasteners

and are rolled or coiled to such a diameter that they retain a set of curvature normally smaller than that of the roller 11. Thus, by positioning the fasteners 10 at intervals along the length of the roller 11, said fasteners serve to securely clamp the end portion 12 (Fig. 7) of the shade fabric 14 in place, as shown in Figs. 2, 8 and 9, their arcuate length being preferably such that they extend more than half way around the circumference of the roller. Alined longitudinal shoulders 15 and 15' (Fig. 2), formed respectively on the longitudinally movable parts 17 and 17' (Fig. 1) of the extensible roller 11 cooperate with longitudinal edges 20 of the fasteners 10 to assure alinement of the fasteners and prevent their displacement on the roller. The shade material is creased between said shoulders and said edges of the fasteners. Preferably, the fasteners 10 are formed at their clamping edges with projections or tongues 21, which extend through openings 22, predeterminedly formed through the fabric 14 at a distance from its upper end or edge, and snugly engage into recesses 24, (see Figs. 2, 6 and 9) formed in longitudinal alinement on the roller 11. A simple method of forming the shoulders 15 and 15' and the recesses 24 will become apparent in the following description.

In the embodiment of the invention shown in the drawings, the roller 11 is of the type generally referred to in the trade as "tin" rollers. The metal sheath of this roller 11 is preferably made in accordance with the process disclosed and claimed in my aforementioned patent. Referring particularly to Figs. 1, 6 and 8, part 17 of the extensible roller 11 consists of a sheet metal strip or strips 25, rolled or curled into circular form, during the process of manufacture, to a diameter smaller than the required diameter of the finished roller, and of a plurality of wooden cylindrical cores or blocks 26, positioned at intervals along the length of the roller within the curved strip or strips 25. The longitudinal margins or edge portions 27 and 29 of the metallic strip or strips 25, when the latter are assembled on the blocks 26, overlap one another, and require no seaming or solder-

100

ing, the tension created in the curved strip or strips 25 upon insertion of the blocks 26 therein maintaining the circular form of the roller throughout its length. Pins or nails 30 may be used to secure the tubular strip or strips to the enclosed blocks 26. If the roller is to be made of a plurality of sections, each consisting of a curved strip 25, the sections may be joined together by means of blocks 31 extending partly within each of the adjacent section ends, and may be secured to them as before described. In this assembly of the sections, they are caused to be so positioned that the longitudinal shoulders 15 formed by the outer overlapping margins 29 of the strips, are brought in alinement with one another, one continuous shoulder being thus formed longitudinally of the roller part 17. Within the roller part 17 is fitted the usual shade rewinding spring and locking devices, (not shown in the drawings), the usual winding key 32 projecting from the outer end of said roller part for proper support in a slotted bracket.

25 Referring to Figs. 1, 4 and 5, part 17' of the roller 11 consists of a separate metallic end section 25', of suitable length and formed in the manner hereinbefore described. Lengthwise adjustment of the roller 11 is provided by a circular wooden core or rod 34, also of suitable length, projecting from the section or innermost section 25, and sliding by extending within the end section 25', a telescoping fit being maintained by the contractile 30 tension of the surrounding sheath 25'; the rod 34 is fixedly secured to the section or innermost section 25 in a manner which will be later described. The outer end of the sheath 25' encloses a wooden plug (not shown in the drawings), secured to the sheath 25' as by 35 nails or pins 30', which plug carries the usual journal pin 35. The overlapping margins 27' and 29' of the sheath 25' require no seaming, the contractile tension being amply sufficient to insure a sufficiently tight grip of said 40 sheath around the rod 34 to give the roller 45 rigidity throughout its length.

In accordance with the invention, respective margins or overlapping free edges of the metallic sections of the roller, are stamped or struck up, during the process of manufacture, at predetermined portions of the roller's length to form protuberances 36; (see Figs. 2 and 6). The latter cooperate with the other overlapping margins, in this case the inner margins 27 and 27', forming shallow pockets or recesses 24, into which the projections or tongues 21 of the fasteners 10 engage, when positioning the latter on the shade and roller. It is to be noted that the process of making the roller 11, as described, is advantageous in that it affords easy and inexpensive means of forming the shoulders 15 and 15', particularly by reason of the fact that the metallic sheaths require no seaming nor solder-

ing, and also forming the recesses 24 and locating all of the latter in longitudinal alignment with one another.

The openings 22, preferably oblong in shape in the direction of the width of the shade fabric, are formed through said fabric at such a distance from its upper end or edge and at such intervals along its width, that, when the shade is properly positioned on the roller, the struck up portions or protuberances 36 lie within said openings 22, thereby rendering the recesses 24 accessible for positioning therein of the tongues 21 of the fasteners 10, and a sufficient length of fabric is provided to be wrapped around the roller beneath the fasteners 10 as shown in Figures 8 and 9. These openings 22 are preferably punched out by means of an instrument, which is positioned along the upper end or edge of the shade fabric 14, whereby proper alignment of the openings 22 and their proper spacing from said upper edge are afforded, obviating the necessity of drawing a line on the fabric prior to forming of the openings. 70 75 80 85

An important feature of the present invention resides in the cooperative action of the side edges 20 of the fasteners 10 with the aforesaid longitudinal shoulders 15 and 15' formed by the outer overlapping margins of the metallic sheaths 25 and 25'. 95

As clearly shown in Figures 8 and 9, the edge portion 12 of the shade fabric 14 is wrapped around the roller in such a direction away from a shoulder 15 or 15' that, when the fasteners 10 are initially positioned over a substantial part of the edge portion 12, they may slide arcuately over said portion 12 toward said shoulder for proper positioning of their tongues 21 within corresponding recesses 24. The shoulder limits this sliding movement of the fasteners 10, and substantial pressure is then applied to the fasteners to insure a firm clamping action of the shoulder and fastener edges 20 on the fabric 12, crimped portions or creases 37 being thus formed in the fabric at the edges of the areas of those portions which are gripped between said shoulder and fastener edges. Thus, when force or tension is applied to the shade 14 during its use, the fasteners 10 are effectively prevented from becoming displaced from their positions, firmly securing the shade on the roller, by the cooperative action of the fastener edges 20 on the shoulder 15 or 15', and the additional friction created by the crimped portions 37 of the fabric materially assists the function of the contractile fasteners 10 in retaining the edge portion 12 of the shade against displacement from its secured position on the roller.

In accordance with the invention, the rod 34 is formed with a longitudinal slot 39, which may conveniently extend throughout its length, and the outer sheath 25 and the sheath 25 adjacent thereto are stamped or 130

struck up at corresponding portions of their adjacent end edges, during the process of manufacture, to form inwardly directed projections or depressions 40 and 41 (see Fig. 4), which extend within the aforesaid slot 39. The depression 40, formed on the section 25, is fixedly secured within the slot 39 by a nail or pin 42, and, if desired, additional means 30 may be used to fixedly secure said section 25 on the rod 34. The depression 41, formed on the section 25', is adapted to slide within the slot 39 longitudinally thereof when adjusting the length of the roller.

From the above description, it becomes apparent that, by reason of the corresponding or duplicate positions of the depressions 40 and 41 on the end edges of the adjacent sections 25 and 25', simple and economical means are provided for alining the shoulder 15, formed by the outer overlapping margin or margins 29 of the section or sections 25, with the shoulder 15', formed by the outer overlapping margin of the end section 25'. In assembling the parts, one end of the rod 34, having the slot 39 thereon, is partly inserted in the section or outermost section 25, with the depression 40 sliding in the slot 39, and said depression 40 is fixedly secured within the slot 39. The other end of the rod 34 is inserted in the section 25', with the other depression 41 sliding in the slot 39, the shoulder 15' immediately alining itself by necessity with the shoulder 15, with no further procedure involved. Rotational movement of the sections 25 and 25' during assembly of the parts is prevented, and arcuate displacement of the shoulder 15' relative to the shoulder 15, when adjusting the roller's length, is also prevented.

If part 17 of the extensible roller 11 is to consist of a plurality of sections 25, the cores or blocks 31, joining these together, may, if desired, likewise be formed with longitudinal grooves, and adjacent ends of the sections 25 likewise formed with corresponding depressions engaging into said grooves, as a means to facilitate alinement of the shoulders 15 in assembling said sections 25 on said blocks 31.

Evidently, by reason of the permanent alinement of the shoulders 15 and 15', the clamping of the shade, by the means hereinbefore described, on both parts 17 and 17' of the extensible roller 11, is greatly facilitated. If desired, a fastener or fasteners, having no tongue 21 formed thereon, may be used to clamp the fabric to the end section 25', the cooperative action of the side edge 20 of a fastener with the shoulder 15' being alone sufficient to maintain the edge portion 12 of the fabric in permanent position on said end section 25'.

The fasteners 10 and shoulder 15 or 15', co-operating therewith, provide a quick and ef-

ficient means of firmly holding the shade fabric in place, and, since they extend around the greater portion of the circumference of the roller, and since succeeding convolutions of the shade are wrapped over them, any displacement from their normal positions is effectively prevented. If the fasteners are provided with tongues 21, the latter also serve to prevent displacement of the fasteners from their clamping position on the roller.

What is claimed is:

1. In a roller device, a roller formed essentially of a metallic sheath having overlapping longitudinal margins, and a fabric fastener comprising a curved strip adapted to overlie a portion of a fabric positioned on said roller, said strip having a portion projecting from one of its longitudinal edges and adapted to extend through the fabric and enter at the outer longitudinal edge of said sheath between the overlapping margins of the latter.

2. In a roller device, a roller comprising a metallic sheath having overlapping longitudinal margins whereby a longitudinal shoulder is formed by the outer longitudinal edge of said sheath, and a fabric fastener comprising a curved strip adapted to overlie a portion of a fabric positioned on said roller, said strip having a longitudinal edge cooperating with said shoulder to grip said fabric therebetween.

3. In a roller device, a roller comprising a contractile metallic sheath formed of a spring metal strip and having overlapping unseamed longitudinal margins whereby a longitudinal shoulder is formed by the outer longitudinal edge of said sheath, and a fabric fastener comprising a curved strip adapted to overlie a portion of a fabric positioned on said roller, said fastener having a longitudinal edge adapted to form a crease in said fabric in co-operation with said shoulder.

4. In a roller device, a roller comprising a metallic sheath having overlapping longitudinal margins, one of said margins being formed with a protuberance forming a recess with the other margin at the outer longitudinal edge of said sheath, and a fabric fastener comprising a curved strip adapted to overlie a portion of a fabric positioned on said roller, said strip having a projection formed on one of its longitudinal edges and adapted to extend through the fabric and enter into said recess.

5. In a roller device, a roller comprising a contractile metallic sheath formed of a spring metal strip and having overlapping unseamed longitudinal margins, one of said margins being formed with a protuberance forming a recess with the other margin at the outer longitudinal edge of said sheath, and a fabric fastener comprising a curved strip adapted to overlie a portion of a fabric positioned on said roller, said fastener having a projection formed on one of its longi-

tudinal edges and adapted to extend through the fabric and enter into said recess.

6. In a roller device, a roller having thereon a shoulder and a recess at said shoulder, and a fabric fastened comprising a curved strip adapted to overlie an inner portion of a fabric, said strip having a projection formed on that one of its edges furthest removed from the inner edge of said fabric, said projection being adapted to extend through said fabric and enter into said recess and said longitudinal edge of said strip serving to grip said fabric in cooperation with said shoulder.
- 10 7. In a roller device, a roller having a shoulder at its outer surface, and a fabric fastener comprising a curved strip adapted to extend over the larger portion of the circumference of said roller to clamp an inner portion of a fabric thereon and to be carried by said roller and clamped fabric portion, said strip having an edge serving to form a crease in the fabric in cooperation with said shoulder when it is positioned on the roller
- 20 25 and fabric thereon and slid arcuately toward said shoulder, said shoulder also serving to prevent arcuate displacement of said fastener.

In testimony whereof, I have affixed my signature to this specification.

30 STEWART HARTSHORN.
